INVENTOR

Samuel William Yeats.

By James W. Masters

His Attorney.

UNITED STATES PATENT OFFICE.

SAMUEL WM. YEATS, OF MONROVIA, CALIFORNIA.

HOOK-AND-EYE FASTENER.

1,340,858.

Specification of Letters Patent. Patented May 18, 1920.

Application filed December 16, 1915, Serial No. 67,249. Renewed April 14, 1920. Serial No. 373,989.

To all whom it may concern:

Be it known that I, SAMUEL WILLIAM YEATS, a citizen of the United States, residing at Monrovia, in the county of Los Angeles and State of California, have invented a new and useful Improvement in Hook-and-Eye Fasteners, of which the following is a specification.

This invention pertains to fasteners for garments, of the class known as hook and eye fasteners, and is designed as an improvement on the devices now in use.

An object of the invention is to provide a hook-and-eye fastener which may be quickly applied to one or more pieces of cloth and secure the edges thereof in a neat and efficient manner.

Other objects are to provide a fastener which is cheap, durable, and practical, and which may be easy to attach and detach from any material, and which can be reused a number of times without destroying the efficiency of the fastener.

Another object is to provide a fastener of the hook-and-eye class which will remain in the hooked position under all ordinary conditions of use.

Another object is to provide a device which is adapted to secure tents, and awnings, and to suspend small articles from the wall.

I attain these objects by providing a pair of hooks one of which is shaped so as to constitute an eye for the other, the hooks being readily attachable to any cloth fabric or similar material, the preferred form being of spring wire.

Referring to the drawings: Figure 1 is a plan view of a fastener constructed in accordance with my invention. Fig. 2, is a side elevation of the same. Fig. 3 shows a cloth fragment with the edges secured with the fastener shown in Fig. 1.

In the forms shown in Figs. 1, 3, each part is formed with a single run of wire, the eye part 11, formed by a loop ending in sharp opposed prongs 12 for attachment to a cloth fabric. The hook portion 13 has similar prongs 14, and the head 15 is so shaped that it cannot become detached from the part 11. The parts are secured together by turning the hook 13 at a right

angle with the eye and passing the hook therethrough.

Fig. 3 shows the fastener applied to cloth fragments *a*, *b*. To apply the fastener the cloth is pinched to form a small loop therein which is passed between the prongs of the part to be attached, and then the cloth is drawn flat.

In the device shown, the parts are bent slightly at the tips, so that when attached to the cloth fabric, the cloth will lie smooth and not wrinkle. The hook portion has a T-shaped head, and is contracted at the middle to form a neck, the parts so interlocking that they must be turned at a substantially right angle for fastening and unfastening.

While simple and efficient means are herein provided for accomplishing the objects of the invention and the elements shown and described are well adapted to serve the purposes for which they are intended, it is to be understood that no limitation is made to the precise construction shown in the drawings but that various changes, alterations, and modifications, may be made which do not depart from the spirit of the invention, the essence of the invention consisting of a hook member and an eye member, each shaped to interlock with the other and not to readily come apart when in the locked position, and each member being easily attachable and detachable from a cloth fabric.

I claim:

In combination, a pair of interlocking members, each having a contracted neck, a spring loop, a T-head, and opposed prongs in close proximity for attaching to a cloth fabric, said members being each formed of a single run of wire formed with angular turns, and said loops being bent at the tip so that the cloth fabric shall be smooth in the locked position of said interlocking members; the members being tilted to lock.

In testimony whereof I hereto affix my signature, this 8th day of December, in the year 1915.

SAMUEL WM. YEATS.

Witnesses:

LEE EICHOLTZ,
J. B. MILHOUSE.
